RAIL BOND

Harold H. Febrey, South Orange, N. J., assignor
to The American Steel and Wire Company of
New Jersey, New York, N. Y., a corporation of
New Jersey

Application July 11, 1931, Serial No. 550,225

2 Claims. (Cl. 173—278)

This invention relates to rail bonds and more particularly to welded rail bond assemblies of the type disclosed and claimed in my copending applications, Serial No. 134,454 filed September 9, 1926 and Serial No. 137,457 filed September 24, 1926 now issued as United States Patents Nos. 2,008,786 and 2,008,787 respectively bearing the date July 23, 1935.

Briefly the rail bond product of my copending application comprises a terminal and at least one flexible conductor buttwelded thereto; the butt-weld union being made to the terminal at a face thereof remote from the face to be attached to the rail face.

15 One of the objects of the present invention is to improve the rail bond product disclosed and claimed in the above identified application.

Another object of the present invention is to provide an improved welded rail bond assembly.

20 Other objects and advantages will become apparent as the invention is more fully disclosed.

In accordance with the objects of the present invention I have found that an improved rail bond product may be obtained by comprising the terminal thereof of two parts or sections, a base part and a shelf part. The two parts are substantially integral and comprised of the same identical electrically conductive metal, the shelf part, however, facilitates the welding of the terminal to a rail face and the base part by being interposed between the shelf and the butt-weld joint of conductor to the base prevents the heating up of the conductor wires during the welding of the terminal to the rail face.

35 Before further disclosing the nature and scope of the present invention reference should be made to the accompanying drawings wherein:

Figs. 1 to 5 inclusive illustrate the rail bond product of the present invention in several views and modifications.

40 Figs. 6 to 13 inclusive illustrate the manner of uniting the rail bond products of Figs. 1 to 5 inclusive to a rail face.

Referring to the drawings the rail bond products illustrated in Figs. 1 to 5 inclusive comprise a terminal consisting of a base portion 1, and a shelf portion 2, to the base portion of which is united at least one flexible conductor 3 at a face 4 remote from the face to which the shelf portion is attached. In accordance with the teaching of my copending application above identified the conductor 3 is united to the face 4 of the terminal base 1 by buttwelding the same thereto. A sleeve 5 encloses the end of the conductor 3, and is also buttwelded to the face 4.

Preferably the terminal is comprised of soft steel stock and may be cast shaped or drop forged to the size, shape or configuration shown. The latter is preferred. For this purpose I have found that a soft steel stock comprising carbon .01-10%; manganese .50-.70%; sulfur .150-175%; and phosphorus .05% max. is preferable. This type of steel has electrical resistivity of 5 microhms per cubic inch or 12.7 microhms per cubic centimeter. When drop forged, the electrical resistivity rises to about 13.5 microhms per cubic centimeter.

The dimensions of the terminals may vary widely depending upon the contemplated service conditions and upon the desired current carrying capacity of the same during the buttwelding of the conductor thereto. In some types of rail bonds the exact configuration of the terminals shown in the drawings in Figs. 1 to 5 inclusive may be departed from without departing essentially from the inventive idea of comprising the base part 1 of such a mass of material that the heat conductivity therethrough during the welding of the shelf part of the terminal to a rail face, is insufficient to deleteriously effect the physical characteristics of the conductor at the point where it is buttwelded thereto. It has been determined that the copper conductor may not be heated to temperatures in excess of 1200° F. to 1400° F. without deleteriously effecting the physical characteristics thereof.

For example, I have found that in the type illustrated in Fig. 1 the base 1 may have a thickness between the face to which shelf 2 is attached and face 4 to which the conductor is welded of approximately $\frac{1}{2}$ inch where the other two dimensions are $\frac{5}{8}$ " x $1\frac{1}{8}$ " respectively.

In the types illustrated in Figs. 2 to 5 inclusive the mass of base 1 varies materially depending upon the contemplated service condition but such variations are usually taken care of by varying the width of the terminal rather than the thickness of the base 1. The thickness or diameter may vary between $\frac{1}{2}$ " to $\frac{3}{4}$ " and the width from $\frac{3}{4}$ " to $\frac{7}{8}$ ". Preferably the terminal has a flattened face 6 to facilitate the mounting of the bond to a rail face. The sides thereof also may be flattened slightly for the same purpose. The thickness of shelf 2 is preferably kept at about $\frac{1}{8}$ ". The overall length of the terminal varies from 1 $\frac{1}{2}$ " to 1 $\frac{3}{4}$ ".

In the design illustrated in Fig. 3 a hook member 7 is provided to facilitate the gripping of a rail. In Fig. 5 the shelf portion 2 is shown displaced at right angles to the longitudinal axis of

the rail bond to facilitate the uniting of the same to a rail.

Referring to Figs. 6 to 13 inclusive, Fig. 6 illustrates the way in which a rail bond of the type illustrated in Fig. 2 is attached to a face of the rail 10. The flattened side face of the rail bond terminal is placed upon the face of the rail and held in position in any convenient manner and the shelf 2 is welded to the rail face in any convenient manner, as for example by flame, arc or electric resistance methods. The type of weld union obtained is illustrated at 8.

Figs. 7 and 8 are a cross-sectional view and a longitudinal sectional view taken along planes 15 7-7 and 8-8 respectively in Fig. 6, and bring out the characteristic features of the rail bond and the proportionate relationship of parts whereby the specific advantages of the present invention are obtained. In Fig. 8 the relative great 20 distance of the conductor 3 from weld 8 and the approximate proportionate size of the interposed mass of base 1 is shown.

Fig. 9 illustrates a second method of uniting the rail bond of Figs. 2 and 4 to a rail face.

25 In Figs. 10 and 12 is illustrated the manner in
which the type of rail bond illustrated in Fig. 1
is united to the face of a rail 10. In this type
of bond the longitudinal edge of the shelf 2 is
abutted next to the rail face and welded thereto
30 by flame or arc welding methods. The over lap-
ping of the edges of shelf 2 protect the butt-
welded union of conductor 3 and base 1 at face
4 thereon from a direct play of the flame or arc.
The thickness of base 1 prevents the conduction
35 of a deleterious amount of heat energy to the face
4 thereof. Fig. 12 is a sectional view taken along
plane 12-12, Fig. 10.

Figs. 11 and 13 illustrate the manner of uniting the rail bond illustrated in Fig. 5 to the base 40 of a rail 10. The hooked over shelf portion 2 is placed upon the base of the rail 10 and welded thereto in any convenient manner substantially as shown.

It is apparent that there may be many modifica-

tions made of the specific embodiments herein disclosed without departing essentially from the nature and scope thereof as may be set forth in the following claims.

What is claimed:

1. Means for making an electrical connection to a rail comprising a stranded conductor and a terminal member attached to the butt end of said conductor, said terminal member consisting of a body portion comprised of a ferrous metal provided with a face to which the end of the conductor is attached and a shelf portion on the opposite side of said body portion shaped to adapt the said shelf portion to be welded to a rail, the thickness of the body portion in between said face and said shelf portion approximating one-half to three-fourths inch and the cross-sectional area thereof being adapted to provide a sufficient volume of said body portion in between said face and shelf portion to prevent the heating up of the end of the conductor during the welding of the said shelf portion to a rail to a temperature deleteriously effecting the physical characteristics of said conductor. 15 20

2. Means for making an electrical connection 25
to a rail comprising a stranded copper conductor and a terminal member attached to the butt end of said conductor, said terminal member consisting of a body portion comprised of a ferrous metal provided with a face to which the end of the conductor is attached and a shelf portion on the opposite side of said body portion shaped to adapt the said shelf portion to be welded to a rail, the thickness of the body portion in between said face and said shelf portion approximating one-half to three-fourths inch and the cross-sectional area thereof being adapted to provide a sufficient volume of said body portion in between said face and shelf portion to prevent the heating up of the end of the conductor during the welding of the said shelf portion to a rail to temperatures approximating 1200° F. and 40 1400° F.

HAROLD H. FEBREY.
